(57) **CLAIM**

The ornamental design for a wrist wrap, as shown and described.

DESCRIPTION

FIG. 1 is a top front perspective view of a wrist wrap, showing my new design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof; and,

FIG. 7 is a bottom plan view thereof.

In the drawings, the equal length broken lines depict elements on the wrist wrap that form no part of the claimed design.
